GEORGE L. BUMBAUGH, OF INDIANAPOLIS, INDIANA, ASSIGNOR OF ONE-HALF TO
ALBERT L. WATTERS, OF INDIANAPOLIS, INDIANA.

PARACHUTING ATTACHMENT FOR BALLOONS.

1,183,796.

Specification of Letters Patent. Patented May 16, 1916.

Application filed October 5, 1914, Serial No. 865,032. Renewed October 8, 1915. Serial No. 54,883.

To all whom it may concern:

Be it known that I, GEORGE L. BUMBAUGH, a citizen of the United States, residing at Indianapolis, in the county of Marion and 5 State of Indiana, have invented a new and useful Parachuting Attachment for Balloons, of which the following is a specification.

It frequently happens that when balloons 10 ascend into the upper air the expansion of gas within the gas bags, due to the reduced pressure of the atmosphere, causes such gas bags to burst and allow the gas to escape. This bursting may arise from other causes 15 also and almost universally it occurs in the upper portion of the gas bag, leaving the lower portion intact. The gas bag collapses on this bursting, but the collapse may take place in any direction ordinarily; if the 20 collapse is by a lateral folding together of the gas bag walls, the balloon drops suddenly, but if it is by a folding in and inversion of the lower half of the gas bag into the upper half a parachute is produced and 25 the balloon descends in safety to the ground by the parachute action.

It is the object of my invention to insure the production of a parachute in case the gas bag of a balloon bursts, by making 30 certain that the lower half of the gas bag will fold up into the upper half. In attaining this object I provide a fabric reinforcement of the gas bag of the balloon at its equator, this reinforcement consisting of a 35 strip of fabric attached at such equator and free at one edge so that it can be laced to the netting over the gas bag. This reinforcement causes the folding of the gas bag in case of bursting to be an upfolding of the 40 lower part of the gas bag into the upper part thereof, as the reinforcement offers a considerable resistance to any other kind of collapsing, so that the formation of a perfect parachute is insured.

45 The accompanying drawing illustrates my invention.

In this drawing Figure 1 is an illustration of a gas bag of a balloon and netting over it; Fig. 2 is a partial section and perspective 50 view showing the construction of the reinforcement and the manner of attaching it to the netting; and Fig. 3 is a sectional view showing how the bottom half of the balloon upfolds into the upper half in case the latter 55 bursts.

The gas bag 10 is shown as a spherical gas bag, with the usual appendix at the bottom, and the usual netting 12 fits over the gas bag 10 and extends downward for supporting the basket. Extending around the 60 gas bag 10 at its equator is a strip of fabric 15, which at its upper edge is suitably attached to the gas bag proper as by several rows of stitching 16. The lower edge of the strip 15 hangs free, and is provided with 65 any suitable number of eyelets 17, through which a cord 18 may be laced when the gas bag is approximately half full of gas in order to fasten the netting 12 to the strip 15, the cord 18 passing in and out over the 70 ropes of the netting 12 and then through the eyelets 17 in an obvious manner. This permits the netting to be removed from the gas bag for packing, but holds the two firmly together when the balloon is in use. 75

In operation, if the upper part of the gas bag 10 bursts, as at 19, the gas within it escapes through the opening thus formed and the walls of the gas bag collapse. However, the reinforcing strip 15 effectively prevents 80 any collapsing around the equator of the gas bag, so that it remains possible only for the walls of the balloon to move toward each other transversely of the equatorial plane, and as by reason of the loss of gas and the 85 consequent collapsing the balloon is now descending, the lower half of the gas bag is caused to invert itself upwardly into the upper half of the gas bag as shown in Fig. 3, to produce a perfect parachute, which is 90 held in proper shape by the netting 12 and reinforcing strip 15. Thus though the gas bag bursts the balloon may descend in safety to the earth. 95

I claim as my invention:

1. In a balloon, the combination of a gas bag, a fabric reinforcing strip fastened around the equator thereof, said reinforcing strip being free at one edge and provided with eyelets, a netting fitting over the gas bag, and a cord for lacing the netting to the reinforcing strip and passing through the eyelets thereof. 100

2. In a balloon, the combination of the gas bag, a fabric reinforcing strip fastened around the equator thereof and in itself furnishing the sole reinforcement of the gas bag, a netting fitting over said gas bag, and means for attaching said netting directly to said reinforcing strip. 105 110

3. In a balloon, the combination of the gas bag, a fabric reinforcing strip fastened around the equator thereof, said reinforcing strip being stitched to the gas bag only at its upper edge and having its lower edge free, a netting fitting over said gas bag, and means for attaching said netting to the lower part of said reinforcing strip.
4. In a balloon, the combination of a gas bag, a fabric reinforcing strip fastened around the equator thereof, said reinforcing

strip being free at its lower edge, and a netting fitting over the gas bag and attached to such free lower edge.

In witness whereof, I have hereunto set 15 my hand at Indianapolis, Indiana, this twenty-ninth day of September, A. D. one thousand nine hundred and fourteen.

GEORGE L. BUMBAUGH.
